UNITED STATES PATENT OFFICE.

JOHN MEHL, JR., OF JERSEY CITY, NEW JERSEY.

DESIGN FOR A BELT-BODY.

SPECIFICATION forming part of Design No. 32,601, dated April 24, 1900.

Application filed March 27, 1900. Serial No. 10,404. Term of patent 3½ years.

To all whom it may concern:

Be it known that I, JOHN MEHL, Jr., a citizen of the United States, and a resident of Jersey City, in the county of Hudson and State 5 of New Jersey, have invented and produced a new and original Design for a Belt-Body, of which the following is a specification.

The essential feature of my design consists in a belt-body having its outer surface embellished with ribs arranged to cross one another at the middle of the back and gradually converging from the middle of the back toward the opposite ends of the belt and raised figures located intermediate of said ribs in 15 proximity to and on opposite sides of the center of the back.

In the accompanying drawings, Figure 1 is a view of the outside of the belt-body, and Fig. 2 is a transverse section along the line 20 2 2 of Fig. 1.

The belt-body as a whole is denoted by A. The ribs which cross each other at the center of the back and gradually converge toward the opposite ends of the belt-body are denoted, respectively, by B B'. The raised figures intermediate of the ribs B B' on opposite sides of the center of the back are denoted, respectively, by C C'.

What I claim is—

The design for a belt-body, substantially as 30 herein shown and described.

In testimony that I claim the foregoing as my invention I have signed my name, in presence of two witnesses, this 23d day of March, 1900.

JOHN MEHL, JR.

Witnesses:

FREDK. HAYNES,
EDWARD VIESER.
